United States Patent

Des. 238,014

Patented Dec. 9, 1975

238,014

SOFT SURFACE FLOOR COVERING OR SIMILAR ARTICLE

Philip Nugent, North Andover, Mass., assignor to Congoleum Industries, Inc.

Filed Feb. 28, 1974, Ser. No. 446,982

Term of patent 14 years

Int. Cl. D6—11

U.S. Cl. D92—4 R

The single figure of the drawing is a plan view of a carpet showing my new design, a design unit being marked off in dash-dot lines.

I claim:

The ornamental design for a soft surface floor covering or similar article, substantially as shown and described.
